[57] CLAIM

The ornamental design for a protector housing for squeezable valve, as shown and described.

DESCRIPTION

FIG. 1 is a top plan view of a protector housing for squeezable valve showing my new design;

FIG. 2 is a side elevational view thereof;

FIG. 3 is a bottom plan view thereof;

FIG. 4 is a left end elevational view of FIG. 2;

FIG. 5 is a right end elevational view of FIG. 2; and

FIG. 6 is a sectional view along line 6—6 of FIG. 2.

FIG. 1

FIG. 2

FIG. 3

FIG. 4

FIG. 5

FIG. 6
